(57) **CLAIM**

The ornamental design for an electric vehicle charging device, as shown and described.

DESCRIPTION

FIG. 1 is a top front perspective view of an electric vehicle charging device showing our new design;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof; and,

FIG. 7 is a bottom perspective view thereof.

The features shown in broken lines in the figures do not represent claimed subject matter.

1 Claim, 7 Drawing Sheets
